UNITED STATES PATENT OFFICE

2,384,832

FIRING RATE REDUCER

Carl W. Gilligan, East Longmeadow, Mass.

Application April 8, 1944, Serial No. 530,081

5 Claims. (Cl. 89-27)

(Granted under the act of March 3, 1883, as amended April 30, 1928; 370 O. G. 757)

The invention described herein may be manufactured and used by or for the Government for governmental purposes without the payment to me of any royalty thereon.

This invention relates to a firing rate reducer for a firearm.

It is an object of this invention to provide an improved firing rate reducer for the reduction of a normal rate of fire of an automatic firearm. Another object of this invention is to provide an improved firing rate reducer capable of full automatic or reduced rate of fire by manipulation of the trigger.

The specific nature of the invention as well as other objects and advantages thereof will clearly appear from a description of a preferred embodiment as shown in the accompanying drawing in which:

Fig. 1 is a longitudinal sectional view of a trigger housing embodying this invention wherein the mechanism is shown in the cocked position.

Fig. 2 is a view similar to Fig. 1 but shown with the rate reducing mechanism in operation.

This invention may be readily adapted to any firearm of the automatic type and comprises essentially a sear tripping rod actuated by a swinging inertia member, similar to a hammer, which receives an impetus from the reciprocating parts of the firearm. The delay in the movement of the inertia member prior to striking the sear tripping rod effectively slows down the firing rate of the firearm.

In Fig. 1 there is shown a trigger housing 1 which is provided to house the elements of the trigger mechanism. A trigger housing of the type disclosed in U. S. Patent No. 1,293,022 to John M. Browning may be conveniently modified to incorporate this invention and will be utilized as a specific example to illustrate this invention. In a suitable horizontal recess on the top of housing 1 there is mounted a sear carrier 2. On the extreme right end of carrier 2 there is pivotally mounted a sear 3 as by a transverse pin 4. A carrier spring 15 surrounds a cylindrical end portion 16 of carrier 2 and is placed between the shoulder formed by such cylindrical end portion of carrier 2 and the end of the recess in housing 1 to cushion the shock resulting from engagement of sear 3 by recoiling members of the firearm as will be later described. A trigger 5 is pivotally mounted within the hollow interior of housing 1 by a transverse pin 6 located in the upper left hand portion of housing 1 as shown in Fig. 1. A disconnector 7 is pivotally mounted on a stud 8 on trigger 5 in such fashion that it

will move upwardly to engage the forward edge 9 of sear 3 when trigger 5 is pulled rearwardly. A sloped surface 37 on disconnector 7 engages a correspondingly sloped surface 38 on carrier 2 when trigger 5 is pulled rearwardly. Such surfaces are provided to cam disconnector 7 off the edge 9 of sear 3 as will be described.

A split leaf spring 10 is provided to engage the forward end of sear 3 to pivot the rear edge 11 of sear 3 into the path of an operating slide 12. Thus the rear edge 11 of sear 3 will engage a sear notch 13 provided on the underside of slide 12. The sear spring 10 also has a downwardly projecting leaf 14 which engages the top surface 15 of disconnector 7. Leaf 14 thus holds disconnector 7 against the edge of carrier 2 as shown in Fig. 1 to insure that such disconnector will always be in position to engage the edge 9 of sear 3 when trigger 5 is pulled rearwardly. A change lever pin 39 having a slot 41 therein is mounted in a transverse hole 40 in housing 1 to permit full automatic or reduced rate of fire as will be described later. A lever (not shown) is provided on one end of pin 39 on the outside of the receiver of the firearm to effect rotation of pin 39 to obtain the full automatic or reduced rate of fire.

An inertia hammer 17 is pivotally mounted within the pistol grip portion 18 of housing 1 by a transverse pin 19. A torsion spring 20 surrounds pin 19 and is connected to hammer 17 in such fashion that spring 20 will bias hammer 17 upwardly into engagement with a plunger 21. The plunger 21 is inserted in a vertical hole 22 in housing 1 as shown in Fig. 1. Plunger 21 is provided with a conical shaped head portion 23 and a cylindrical stem portion 24. The conical head portion 23 projects sufficiently above the trigger housing 1 so that plunger 21 will be struck by the correspondingly sloped end 42 of slide 12 when such slide travels rearwardly. Sear 3 is bifurcated to permit head 23 of plunger 21 to pass between such bifurcation and contact slide 12. A suitable recess 25 is provided on the underside 45 of slide 12 to accommodate plunger 21 when slide 12 is in the recoiled position as shown in Fig. 1. A spring 26 surrounds stem portion 24 of plunger 21 and is placed within a counterbored portion 27 of hole 22 to bias plunger 21 upwardly against slide 12.

A sear trip rod 28 is inserted in an upwardly sloped hole 29 in trigger 5. A transverse pin 33 provided in trigger 5 engages a slot 34 on the edge of trip rod 28 to limit the longitudinal movement and prevent rotation of trip rod 28 within

trigger 5. Rod 28 projects upwardly thru a suitable hole 36 in carrier 2 to engage the bottom surface of sear 3. The end 30 of trip rod 28 which engages the bottom surface of sear 3 is suitably beveled so as to provide a large engagement area with the bottom of sear 3. The other end of trip rod 28 projects downwardly into pistol grip 18. A surface 31 angularly inclined relative to the axis of the trip rod 28 is provided on the bottom end of rod 28 and a corresponding surface 32 is provided on hammer 17. The surfaces 31 and 32 are engaged by movement of the rear end of rod 28 adjacent hammer 17 when trigger 5 is pulled rearwardly. A sloped surface 35 is provided on the upper corner of hammer 17 as shown in Fig. 1 to strike the end of trip rod 28 as will be presently described.

With the firearm in the cocked position as shown in Fig. 1, that is, with the sear 3 in engagement with sear notch 13 in slide 12, and notch 41 of change lever pin 39 in the position shown, the firearm (not shown) is ready to be fired. When trigger 5 is pulled rearwardly, the rear surface of such trigger enters slot 41 of pin 39 and the disconnector 7 is forced upwardly against the end 9 of sear 3, forcing the end 11 of sear 3 out of engagement with sear notch 13. At the same time trip rod 28 is moved rearwardly so that the end of such rod is opposite sloped surface 35 of hammer 17. Slide 12 under the bias of an operating spring (not shown) goes forward to effect discharge of a cartridge in the firearm (not shown) and simultaneously disconnector 7 slips off the end 9 of sear 3 due to the camming action of sloped surface 31 of disconnector 7 striking sloped surface 38 of carrier 2. Immediately upon discharge of such cartridge, slide 12 is forced rapidly rearwardly by the automatic mechanism of the firearm and in so doing the end 42 of slide 12 strikes the conical head 23 of plunger 21 driving the plunger smartly downward. The force of such blow is transmitted to hammer 17 by plunger 21 whereupon hammer 17 is rotated in a clockwise direction about pin 19.

In the meantime slide 12 travels rearwardly until it strikes the buffer mechanism of the firearm (not shown). Upon the return travel of slide 12, sear 3 engages sear notch 13 thereby holding slide 12 in the position shown in Fig. 1. The end 11 of sear 3 is of course, returned into the path of slide 12 by sear spring 10. It should be appreciated that the time elapsing between slide 12 striking the buffer (not shown) and returning to the point where it again is caught by sear 3, is of extremely short duration.

With slide 12 again engaged by sear 3 the hammer 17 has about completed its downward travel and is about to be returned upwardly by torsion spring 20. As trigger 5 is still held in the rear position for automatic fire, the end of trip rod 28 will then be in the path of hammer 17 when hammer 17 is again returned to the position shown in Fig. 1 by torsion spring 20. Hammer 17 will then strike the end of rod 28, the surface 35 on hammer 17 coming in contact with the end of rod 28. The inertia of hammer 17 drives trip rod 28 forwardly to raise the forward end 9 of sear 3 which brings the rear end 11 of sear 3 out of engagement with sear notch 13 in slide 12. Hence slide 12 moves forwardly to again effect discharge of the firearm, whereupon the cycle will be repeated as long as trigger 5 is held rearwardly.

As the time required for hammer 17 to complete its cycle of movement is substantially greater than the time required for slide 12 to

travel its cycle from where it strikes plunger 21 to the buffing mechanism and return to where it is again held in engagement with sear 3, there is a considerable delay introduced between successive shots and accordingly a substantial reduction in the firing rate.

The normal automatic rate of fire of the firearm is readily obtained by rotating change lever pin 39 by the change lever (not shown) until slot 41 is out of the path of trigger 5. This limits the rearward travel of trigger 5 so that the end of trip rod 28 cannot come into the path of inertia member 17. Thus the rate reducing mechanism is rendered inoperative. The upward movement of disconnector 7 is likewise limited by restricting the rearward movement of trigger 5. The limited rearward movement of trigger 5 will now permit disconnector 7 to raise only sufficiently to disengage the rear edge 11 from sear notch 13. As disconnector 7 stays in contact with sear 3 as long as trigger 5 is held rearwardly the firearm will fire full automatically.

With slot 41 in the position shown in Fig. 1 so that trigger 5 will enter such slot thereby making the rate reducing device operative the firearm can be readily fired fully automatically or at the reduced rate of fire by careful manipulation of the trigger. Pulling the trigger back but a slight amount will permit full automatic fire while pulling the trigger all the way to the rear permits reduced rate of fire.

It is thus apparent that a rate reducing device embodying this invention is of simple, rugged construction and will effect a substantial reduction in the cyclic rate of the firearm.

I claim:

1. In a firearm having a reciprocating slide and a pivoted sear engageable therewith, in combination, a pivoted inertia member, a spring pressed plunger arranged in the recoil path of the slide, cooperating cam surfaces on said slide and said plunger constructed to force said plunger axially by recoil movement of the slide, said inertia member having a portion disposed in the path of said plunger whereby a rotational force is imparted to said inertia member, resilient means opposing said rotation, and a disconnecting member having one end engageable by said inertia member during the return movement thereof and the other end arranged to disconnect the sear from the slide by the impact of said inertia member on said disconnector.

2. In a firearm having a reciprocating slide and a pivoted sear engageable therewith, in combination, a pivoted inertia member, means energized by the slide for applying a rotational force to said inertia member, resilient means opposing said rotation, a pivoted trigger, means on said trigger for momentarily pivoting the sear out of slide engaging position by pulling of said trigger, and a plunger slidably mounted in said trigger, one end of said plunger, in the pulled position of said trigger, arranged to be engaged by said inertia member in its return movement, the other end of said plunger arranged to pivot the sear out of slide engaging position by the force received from said inertia member.

3. In a firearm having a reciprocating slide and a pivoted sear engageable therewith, in combination, a pivoted inertia member, a spring pressed plunger arranged in the recoil path of the slide, cooperating cam surfaces on said slide and said plunger constructed to force said plunger axially by recoil movement of the slide, said inertia member having a portion disposed in the

path of said plunger whereby a rotational force is imparted to said inertia member, resilient means opposing said rotation, a pivoted trigger, means on said trigger for momentarily pivoting the sear out of slide engaging position by pulling of said trigger, a plunger slidably mounted in said trigger, and one end of said plunger, in the pulled position of said trigger, arranged to be engaged by said inertia member in its return movement, the other end of said plunger arranged to pivot the sear out of slide engaging position by the force received from said inertia member.

10

4. The combination defined in claim 2 plus manually operated means for selectively holding said disconnecting member out of engagement with said inertia member.

5. The combination defined in claim 3 plus manually operated means for limiting said movement of said trigger whereby said plunger is maintained out of engagement with said inertia member.

CARL W. GILLIGAN.
